(57) **CLAIM**

The ornamental design for a cat litter pan set as shown and described.

DESCRIPTION

FIG. 1 is a front, right, top perspective view of a cat litter pan set showing my new design;
FIG. 2 is a front view thereof;
FIG. 3 is a back view thereof;
FIG. 4 is a left view thereof;
FIG. 5 is a right view thereof;
FIG. 6 is a top view thereof; and,
FIG. 7 is a bottom view thereof.

The broken lines shown on the drawings depict portions of the cat litter pan set that form no part of the claimed design.

1 Claim, 7 Drawing Sheets
